UNITED STATES PATENT OFFICE.

JERE L. WENTZ, OF PASSAIC, NEW JERSEY.

MASSAGE MACHINE.

Application filed November 23, 1925. Serial No. 70,748.

My invention is for an improvement in massage machines.

An object of my invention is to provide a bank or row of machines which may be operated by a common drive shaft. This will allow several persons to be served by a single driving medium. Another object is to mount the drums of the machines eccentrically of the drive shaft so that an oscillatory as well as a rubbing pressure with motion action is produced. A further object is to provide means for producing a kneading action during the massaging caused by the rotating drum, which will be similar to that accomplished by rubbing with the hands. A still further object is to attain the variation in pressure which is accomplished by a trained masseur.

I accomplish these objects by the device illustrated in the accompanying drawings, in which—

Figure 1 is an elevation partly in section of the bank or row of machines and the motor attachment,

Figure 2 is a cross section on line 2—2 of Figure 1,

Figure 3 is a detail view,

Figure 4 is an elevation of a modified form of roller.

Similar characters of reference refer to similar parts thruout the several views.

The machines 5, 5 are mounted on a common drive shaft 1. On either side of each machine is an inverted U shaped support 2 including posts and cross bars which serve a double function, namely as a mounting for the machines and also as a hand grip of which more will appear intra. Fixed across each of the pairs of legs of the support members 2, 2 is a bar 3, 3 having journals 8, 8, therein, thru which is mounted the drive shaft 1.

At one end of this shaft is a train of gearing 11 which connects the said shaft to an operating means 4 which is preferably an electric motor.

As all of the massage machines of the bank are similar, a detailed description of but one will be given. However it is to be noted that the body contact members or rollers may vary as to their surface structure, of which more will be said hereinafter.

Each machine includes a drum having circular side plates 6, 6, which are perforated around their peripheries, to receive rollers 7, 7. The plates are fixed to the shaft 1 to

rotate therewith, and are eccentrically mounted thereon. In the perforations 9 of the plates 6, 6 are loosely journaled the pins 10 which serve to support and are fixed in the ends of said rollers. These pins are eccentric of the axes of the rollers 7, 7.

In operation the person wishing a massage, having first started the motor 4, grasps the hand grips 2, 2 whereby pressure of the body or part to be massaged is exerted against the rotating drum. It is apparent that the drum may be straddled to massage the inside of the legs, or a limb may be placed across the drum, or the torso held thereagainst. As the drum rotates, due to its eccentric mounting it will gradually press against the part offered thereto, increasing the pressure as it rotates and will then upon continued rotation relieve the pressure thus completing a cycle. Upon contact of the part to be massaged with the drum, the loosely mounted rollers will be rotated. These rollers are also eccentrically mounted so that a kneading action will occur as they rotate and pass over the part offered. The result will be that the part offered to the drum will be rubbed and kneaded simultaneously. The pressure exerted by the drum will be controlled by the person operated upon, depending upon the weight of the body and the force exerted by said person against the drum by means of the hand grips.

A modified form of roller 12 is shown in Fig. 4 which may be substituted for the rollers of Fig. 1, depending upon the particular action desired. It is of course understood that other roller types having varied surfaces may be employed as desired, in lieu of the types shown herein.

Having thus described my invention, what I claim is:

1. In a device of the character described, the combination of a plurality of U-shaped supports, hand holds thereon adjacent the upper ends thereof, bars on the supports, a rotatable drive shaft carried by said bars, means for rotating the said drive shaft, a plurality of circular plates mounted on said drive shaft and arranged in pairs and having perforations in their peripheral margins, pins in said perforations and rollers eccentrically mounted on said pins whereby a body resting on said rollers may be massaged thereby.
2. A massage machine adapted to support

a body to be massaged thereby and including in combination a drive shaft, drums fixed eccentrically on said drive shaft, rollers eccentrically mounted in the peripheries of said drums, posts adapted to support said shaft and hand holds on said posts.

3. A massage machine adapted to support a body to be massaged thereby and including in combination a drive shaft, spaced

parallel plates mounted eccentrically on said shaft and having peripheral perforations, pins therein and rollers eccentrically mounted on said pins, posts supporting said drive shaft and a hand hold carried by said shaft adapted to be grasped by a person resting on said rollers.

In testimony whereof I affix my signature.

JERE L. WENTZ.
